UNITED STATES PATENT OFFICE.

ELIZABETH D. CONROY, OF MEMPHIS, TENNESSEE.

EXTENSIBLE SHELF.

1,262,021.

Specification of Letters Patent.

Patented Apr. 9, 1918.

Application filed April 4, 1917. Serial No. 159,726.

To all whom it may concern:

Be it known that I, ELIZABETH D. CONROY, a citizen of the United States, residing at Memphis, in the county of Shelby and State 5 of Tennessee, have invented certain new and useful Improvements in Extensible Shelves, of which the following is a specification.

This invention relates to improvements in supports, and more particularly to shelves 10 such as are used in bath rooms, barber shops and the like.

The main object of the invention is to provide a shelf of this character, the supporting member of which while extensible 15 to adapt it for shelves of varying lengths, is designed to be completely concealed when applied and thereby avoids all danger of screws being pulled out and leaving unsightly breaks in the plaster of the wall on 20 which the shelf is mounted.

Another object is to provide a shelf of this character equipped with a depending towel rack.

With the foregoing and other objects in 25 view, which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

In the accompanying drawings:

35 Figure 1 represents a front elevation of a portion of a wall showing this improved shelf applied, a coating surface or plaster of the wall being broken away to show the shelf support beneath it.

40 Fig. 2 is a horizontal section taken on the line 2—2 of Fig. 1, and

Fig. 3 is a transverse vertical section taken on the line 3—3 of Fig. 1.

In the embodiment illustrated, this improved shelf consists of an attaching member in the form of a series of links 1 and 2 pivoted together to form a well known "lazytongs", the construction being such that these links can be extended or contracted in the well known manner.

55 Bars 3 and 4 are connected with the terminals of the links at opposite ends of the supporting member, any desired number of which links may be employed according to the lengths of the shelves to be supported, seven pairs of said links being here shown,

although obviously the device is not to be restricted to such number. These bars 3 and 4 are designed to be connected to the lathing or uprights of a wall before the latter is plastered. These bars are provided with apertures to receive fastening screws indicated at 5, and have secured thereto intermediate of their ends, preferably midway thereof, laterally extending shelf supporting arms 6 and 7, which may be of any desired length according to the width of the shelf to be carried thereby. These arms are provided at their free ends with upturned fingers 8 shown clearly in Fig. 3 70 and which are designed to act as stops for holding the shelf 9 in position on said arms, the shelf being of a width to fit between the outer face of the wall W on which the shelf is mounted and said fingers. The 75 shelf is preferably composed of glass but may be of any suitable material.

Depending from the arms 6 and 7 are two hook-shaped members 10 which are designed to receive and support a rod 11 adapted for 80 use as a towel rack, said rod being preferably composed of metal, nickel-plated or otherwise finished to suit the purchaser, although obviously it may be of wood or other material if found desirable.

85 From the above description it will be obvious that the lazytong support may be extended or contracted to adjust it to suit the length of shelf to be mounted thereon and then secured to the end pieces and that after 90 it is placed in position and the plaster or other coating for the wall placed thereover, there is no danger of said support pulling away from this mounting and the only parts exposed will be arms 6 and 7 with the hook-like hangers 10 depending therefrom and on which any suitable shelf 9 and rod 11 95 may be mounted. While two of these arms 6 and 7 only are shown, it is to be understood that any desired number may be employed according to the length and the weight of the shelf to be supported.

The arms 6 and 7 while here shown connected with the bars 3 and 4 by laterally extending flanges or feet 12, may be secured 105 thereto in any other desired manner, said feet being here shown riveted to said bars.

110 From the foregoing description, taken in connection with the accompanying drawings, the advantages of the construction and of the method of operation will be readily apparent to those skilled in the art to which

the invention appertains and while I have described the principle of operation of the invention together with the device which I now consider to be the best embodiment thereof, I desire to have it understood that the device shown is merely illustrative and that such changes may be made as are within the scope of the claimed invention.

I claim:—

- 10 1. In a shelf, the combination of a lazytongs, means for connecting said lazytongs to a supporting structure, arms projecting laterally from said tongs, and a shelf removably supported on said arms.
- 15 2. The combination with a lazytongs having bars connecting the links at the ends thereof, arms projecting laterally from said bars and having upturned fingers at their

free ends, and a shelf supported on said arms.

3. The combination with a lazytongs having means for connection with a supporting structure, a concealing coating arranged over said tongs, arms extending laterally from opposite ends of said tongs through 25 said coating and having stops spaced from the inner ends thereof, and a shelf removably mounted on said arms between said coating and said stops.

In testimony whereof I affix my signature 30 in presence of two witnesses.

ELIZABETH D. CONROY.
